UNITED STATES PATENT OFFICE.

GEORGE L. MENK, OF ST. LOUIS, MISSOURI.

HEATER.

Application filed November 19, 1923. Serial No. 675,548.

To all whom it may concern:

Be it known that I, GEORGE L. MENK, a citizen of the United States, residing in the city of St. Louis and State of Missouri, have 5 invented a new and useful Improvement in Heaters, of which the following is a specification.

This invention relates to heaters and more particularly to such employing an electrical 10 heating element. It has for its objects to secure maximum efficiency from a minimum of wattage in the heating element; to distribute the heat by forced circulation of air through the heater rather than by radiation; 15 and to attain certain advantages as will more fully appear in the following description.

The invention consists in the novel construction, parts, and combinations and arrangements of parts as hereinafter set forth 20 and pointed out with particularity in the appended claims.

In the accompanying drawings illustrating 25 a practical adaptation of the invention,—

Figure 1 is a side elevation of the heater, a portion of the side wall of the shell being broken away to show some of the interior arrangements;

30 Figure 2 is a vertical section taken on or about the line 2—2 of Figure 1; and

Figure 3 is a view, partly in top plan and partly in horizontal section.

Referring now to the drawings, the numeral 1 designates generally the hollow shell 35 or housing of the heater, which, as shown, is of rectangular form, but, obviously, may be cylindrical or of other forms, as may be desired. This shell is closed throughout except for certain air inlet and outlet apertures which are provided for purposes as 40 will be later specified.

The shell is mounted on suitable feet or legs 2 to support it from the floor or plane 45 on which it is placed in use.

Extending up from the center of the bottom 3 of the shell is an ordinary commercial electrical heating element 4, surrounding which is an annular upwardly flaring flange 50 or funnel 5, while in the bottom 3 is a series of apertures 6 in circular arrangement adjacent to said flange or funnel 5.

Surrounding the flange or funnel 5 is a 55 series of vertical tubes 7, said tubes being fitted tight in apertures provided therefor in the bottom 3 and extending up to a plane

somewhat above the flange or funnel 5 and being supported at their upper ends by an annular horizontal flange or ledge 8 secured on the inner faces of the side walls of the 60 shell.

Above the tubes 7 is a baffle 9, preferably comprising a plate or sheet which is flanged at its margin and riveted or otherwise secured to one side wall of the shell, as at 10, 65 thence extended upward at an incline to approximately the middle of the shell, and then rebent and extended horizontally, as at 11, back to the side wall of the shell and there secured, as at 12. This baffle is also 70 fastened at its ends, as at 13, 14, to the adjacent side walls of the shell, thereby completing and constituting a chamber 15 which is closed except for a series of apertures 16 in the side wall and a series of tubes 17 75 communicating therewith through the plate 11.

The tubes 17 extend up vertically and terminate some distance below the top of the shell and are supported at their upper 80 ends by a cross-bar or plate 18, which latter is secured at its ends to the opposite side walls of the shell.

In the top cover plate 19 of the shell is a multiplicity of apertures 20 for outlet of 85 the heated air in the shell, while in one of the side walls an opening 21 is provided so as to gain access to the interior as occasion may require, said opening 21 being normally closed by a suitable door or removable 90 closure 22.

In the operation of the heater, the electrical heating element 4 being energized, the heat is concentrated and reflected upward and outward by the arrangement of the annular upwardly flaring flange or funnel 5, thereby preventing the bottom 3 of the shell 95 1 from becoming heated to a high degree, it being of course understood that it is desirable to prevent wasteful dissipation 100 of heat at the bottom of the heater as well as to make for safety in holding down the temperature at that portion of the heater.

The upper portions of the tubes 7 become heated, thereby causing an upward 105 draft through them and, consequently, the outside air is drawn into the tubes from beneath the bottom 3. Air is also drawn in through the apertures 6 and into contact with the conical flange 5 so as to take up a 110 certain amount of the heat which is radiated therefrom and thereby further preventing

the bottom 3 from becoming unduly heated.

The baffle sheet 9 also becomes heated owing to its location above the element 4, and the air in the chamber 15 in turn be-
5 comes heated and rises in the tubes 17 which also have become heated so as to cause an upward draft through them, the outside air being thereby drawn into the chamber through the apertures 16.

10 The heated air in the shell 1 from the tubes 7, 17, and apertures 6, passes out through the apertures 20 in the top plate 19, the several apertures 20 and the inlets and tubes being, of course, proportioned and
15 correlated so allow the air to become heated thoroughly before being discharged from the shell.

By the correlated construction and arrangement herein set forth a forced circulation is set up in the shell and a greater efficiency is attained from an electrical heating element of a given wattage than is possible from mere reflection and radiation.

Obviously the heater admits of considerable modification and alteration within the spirit of the invention as defined by the appended claims. It is, therefore, not limited to the specific construction and arrangement shown in the accompanying drawings.

30 What is claimed is:

1. In a heater, a hollow shell, a heating element at the bottom of the shell, an upwardly flaring, reflecting flange surrounding said heating element, a series of vertical tubes surrounding and contiguous to said reflecting flange, said tubes being open at their lower ends through the bottom of the shell and extending up to a plane above the upper edge of said reflecting flange, and
35 the shell having outlet openings in the upper portion thereof.

2. In a heater, a hollow shell, a heating element at the bottom of the shell, an upwardly flaring, reflecting flange surrounding said heating element, a series of vertical tubes surrounding and contiguous to said reflecting flange, said tubes being open at their lower ends through the bottom of the shell and extending up to a plane above
40 the upper edge of said reflecting flange, an overhanging baffle projecting from the wall of the shell above said heating element and the plane of the upper ends of said tubes, said shell having outlet openings above said baffle.

55 3. In a heater, a hollow shell, a heating element at the bottom of the shell, a reflecting flange surrounding said heating element, said flange extending from the bottom

of the shell and being upwardly flaring, a series of apertures in the bottom of the shell, surrounding but underlying within the radius of the upper marginal portion of said flange, a series of vertical tubes surrounding said reflecting flange, said tubes being open at their lower ends through the bottom of the shell and extending up to a plane above the upper edge of said reflecting flange, said shell having outlet openings in the upper portion thereof.

4. In a heater, a hollow shell, a heating element at the bottom of the shell, an upwardly flaring flange surrounding said heating element, a series of apertures in the bottom of said shell surrounding said flange in relatively close proximity thereto, a series of vertical tubes surrounding said flange, said tubes being open at their lower ends through the bottom of the shell and extending up to a plane above the upper edge of said flange, said shell having a chamber above said heating element and the plane of the upper ends of said tubes, the bottom wall of said chamber constituting a baffle, a series of vertical tubes having their lower ends in communication with said chamber and their upper ends extending up to a plane below the top of said shell, said chamber having air inlet openings and said shell having outlet openings above the plane of the upper ends of said second mentioned tubes.

5. In a heater, a hollow shell, a heating element at the bottom of the shell, an upwardly flaring flange surrounding said heating element, a series of apertures in the bottom of the shell surrounding said flange in relatively close proximity thereto, a series of vertical tubes surrounding said flange, said tubes being open at their lower ends through the bottom of said shell and extending up to a plane above the upper edge of said flange, said shell having a chamber above said heating element and above the plane of the upper ends of said tubes, the bottom wall of said chamber inclining upward from one side wall of the shell to approximate the middle thereof and the top wall of said chamber being substantially horizontal, said chamber having inlet opening through said side wall of the shell, a series of vertical tubes having their lower ends open to communication with said chamber through the upper wall thereof and extending up to a plane below the top of the shell, said shell having outlet openings in the upper portion thereof.

GEORGE L. MENK.
